(57) **CLAIM**

The ornamental design for a spray bottle, as shown and described.

DESCRIPTION

FIG. 1 is a perspective view of a spray bottle showing my new design, including an unclaimed trigger spray closure; FIG. 2 is a perspective view thereof in the open position; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; and, FIG. 9 is a cross section view taken along the line 9-9 in FIG. 7.

The broken lines depict portions of the article that form no part of the claimed design.
